UNITED STATES PATENT OFFICE

2,040,403

ELECTRO-HYDRAULIC CONTROL
STRUCTURE

Lawrence M. Persons, Des Moines, Iowa, assignor
to Penn Electric Switch Co., Des Moines, Iowa,
a corporation of Iowa

Application January 31, 1934, Serial No. 709,201

1 Claim. (Cl. 60—52)

The object of my invention is to provide an electric control structure which is simple, durable and comparatively inexpensive to manufacture, the present application being a continuation in part of my co-pending application Serial No. 631,892 filed September 6, 1932 now Patent No. 2,020,618.

A further object is to provide a control structure electrically operated for the purpose of opening a valve or operating other controlling devices whenever energized, said structure upon being de-energized allowing said valve or other device to return to its initial position.

Still a further object is to provide in combination with a controlling device constrained to remain in one position, means for moving it to an opposite position whenever such means is energized and for maintaining the controlling device in such opposite position until deenergization of the means so that the controlling device can then be returned to its first position because of being constrained toward such position.

Still a further object is to provide a controlling device and means for moving it from one position to another comprising an expansible pressure chamber in operative connection with the controlling device and an electrically operated pump for supplying fluid pressure to the pressure chamber, the controlling device being arranged with stop means so that when it assumes a position because of expansion of the pressure chamber the pump can continue to operate because of the slippage of the medium supplied to the pressure chamber relative to the pump so that when an electric motor is used for operating the pump it will then continue to operate as long as energized, the continuing operation being at a relatively low speed but not stalling the motor.

Still a further object is to provide a connection between an oil pump and a controlling device which includes a movable member automatically operable to permit by-passing of the oil from the controlling member around the pump when return movement of the controlling member occurs.

Still a further object is to provide a control device comprising a valve, the valve plug of which is resiliently mounted in such manner that snap action is secured during the closing and opening movements of the valve.

With these and other objects in view my invention consists in the construction, arrangement and combination of the various parts of my device, whereby the objects contemplated are attained, as hereinafter more fully set forth, pointed

out in my claim and illustrated in the accompanying drawing, in which:

Figure 1 is a side elevation of an electric control structure embodying my invention.

Figure 2 is an enlarged vertical sectional view of the same.

Figure 3 is a sectional view of a portion of Figure 2 showing the parts in a different position; and

Figure 4 is a sectional view of a portion of Figure 2 on a reduced scale showing the valve in a different position.

On the accompanying drawing I have used the reference character A to indicate a gas valve. This valve may be used in connection with gas furnaces or the like for controlling the supply of gas thereto, although instead of being a gas valve it can be any other control device adapted to be moved to opposite positions by the electric mechanism B which I provide for operating the valve A.

The valve A includes a body 10 having an inlet 12 and an outlet 14. Between the inlet and the outlet a seat 16 is provided against which a valve disc 18 is adapted to seat.

For actuating the valve disc 18 to closed position I provide a spring 20 interposed between a packing 22 and piston 24. The piston 24 is mounted on a valve stem 26 which in turn is connected with the valve disc 18. The manner of connection is by means of a pin 27 extending across a socketed boss 28 of the valve disc 18 and through a slot 30 of the upper end of the valve stem which end is received in the socket of the boss 28. A spring 32 is interposed between the boss 28 and a cover cup 34, resting against a shoulder of the valve stem 26.

The piston 24 is reciprocable in a cylinder 36, the piston and cylinder forming an expansible pressure chamber. Beneath the cylinder 36 is an electric motor having field laminations 38 and armature laminations 40. Field coils are indicated at 42 and the motor is preferably of the shaded pole type so that it can be either stalled or its speed cut to a minimum without harming the motor, even though it remains energized.

The armature 40 is secured to a shaft 44 which has an off-center crank pin 46. A pump is provided in the form of radially extending cylinders 48 having pistons 50 therein. Wrist pins 52 extend from the pistons 50 and are connected by connecting rods 54 to pins 56 of discs 58. The discs are pivoted on the crank pin 46, the entire pump structure being fully disclosed in my Patent No. 2,020,618 above referred to.

- The right hand connecting rod 54 is preferably a master rod and I have shown brazing at 60 to rigidly connect it with the discs 58 whereby the discs and this rod form a master rod. 5 The electric motor is enclosed in a casing 62 while the pump is enclosed in a casing 64. The casing 62 constitutes a reservoir for oil 66 which, when the motor and pump are operated, flows through an intake port 68 in the shaft 44 to the cylinders 48 when the pistons travel outwardly therein. An outlet port 70 provides for escape of the oil from the cylinders when the pistons move inwardly, this oil escaping as indicated by the arrows into the pump casing 64. 10 15 The pumped oil flows through a passageway 12 to a by-pass valve plug 74 slidable in a bore 15 and opens a check valve 76 therein and then flowing through a passageway 18 to the cylinder 36. The check valve 76, however, is not opened until the plug 74 is slid toward the left 20 to seat against a valve seat 79 and thereby plug up a by-pass port 80 as shown in Figure 2. 25 The cylinder 36 may be provided with a port 37 through which the oil may return to the reservoir 62 if this type of construction is desirable.

Practical operation

This control structure is adapted for use in connection with a room thermostat or other controlling device whereby when the room thermostat calls for heat it energizes the motor for opening the valve disc 18 and permitting gas to flow to the furnace to augment the fire. The spring 20 returns the valve disc to closed position when the motor is de-energized, caused by the heat requirements of the thermostat being satisfied. 30 35

Upon energization of the motor, the oil 66 normally within the reservoir casing 62 is 40 pumped, as indicated by the arrows in Figure 2, to first close the by-pass port 80 by moving the plug 74 in the bore 75 toward the left and then the pressure is built up until the spring closed check valve 76 is opened so that the oil 45 can flow into the pressure chamber to raise the piston 24.

The valve disc 18 will first be in the full line position of Figure 4 and after the piston 24 and the valve stem 26 are raised the spring 32 will 50 be compressed, the pin 27 and the slot 30 permitting lost motion. The valve disc 18 will remain seated, due to the pressure of the incoming gas until the bottom of the slot 30 engages the pin 27 and raises the valve disc slightly. The 55 gas will then rush under the disc. This, together with the expanding tendency of the spring 32 will quickly snap the disc to a substantially open position as shown by dotted lines in Figure 4.

The piston 24 will continue to rise until the valve is wide open, whereupon it will be stopped in the position of Figure 2 by the spring 20 being closed, or some other mechanical stop means, and thereafter the motor will operate at a much 65 slower speed, depending upon how much slippage of oil there is through the pump.

The port 37 is optional. If it is used, then of course the oil beneath the piston 24 will flow through it when the piston rises high enough 70 to uncover this port. This will prevent any further upward movement of the piston and the

motor can still rotate at the same speed if the port is large enough, or at a somewhat reduced speed if the area of the port is small enough to offer more resistance of the flow of oil than the spring 20 does to the travel of the piston 24. 5

When the motor is de-energized, the oil pressure in the passageway 12 will be reduced by the slippage of oil through the pump and the spring 20 will operate to first push the plug 74 toward the right and against a stop 77, as in Figure 3, 10 and then to quickly expel the oil from beneath the piston 24 through the by-pass port 80 into the reservoir 62. The valve disc 18 will first assume the dotted line position of Figure 4 and soon thereafter the rush of gas through the valve seat 15 16 will cause the disc to seat with a snap action compressing the spring 32 as shown by full lines in Figure 4 and soon after this the valve stem 26 will have reached its lower limit of movement.

The automatically operable valve plug 74 permits a much quicker return of the oil than if it were permitted to leak slowly through the clearance spaces in the pump. As soon as the oil starts to return, the by-pass port 80 is open so that the movement of the returning oil is then 25 unimpeded.

Some changes may be made in the construction and arrangement of the parts of my device without departing from the real spirit and purpose of my invention, and it is my intention to 30 cover by my claim, any modified forms of structure or use of mechanical equivalents, which may be reasonably included within their scope.

I claim as my invention:

In a control structure, a controlling device 35 movable to opposite positions, means constraining said device to remain in one of said positions and mechanism to move said controlling device to its opposite position against such constraint, said mechanism comprising a pressure 40 chamber, a medium therein, said pressure chamber being in operative connection with said controlling device to move it to such opposite position upon said medium being placed under pressure, a reservoir, a pump having an intake connected with said reservoir and an outlet connected with said pressure chamber, said last connection including a bore having a stop at one end and a valve seat at its other end, communicating with said reservoir and a movable member 45 therein adapted to be moved toward said valve seat by the medium as it passes through said bore and to engage and close said valve seat, said movable member when in an opposite position engaging said stop and permitting return of said 50 medium from said pressure chamber to said reservoir through said valve seat, said member when in said first position preventing such passage of said medium, check valve means in said member for permitting restricted flow only of the medium 55 from the pump to the pressure chamber when said member is in said first position, means for stopping the movement of said controlling device when it assumes its opposite position, and means for operating said pump to place said medium 60 under pressure, said last named means when inoperative allowing the pressure of said medium to reduce and said movable member to thereby be moved by said constraining means away from said valve seat to permit return of said medium. 65 70
